UNITED STATES PATENT OFFICE.

FRANK K. EWING, OF WORCESTER, MASSACHUSETTS, AND STANLEY R. CUMMINGS, OF CANTON, OHIO, ASSIGNORS TO THE HOOVER COMPANY, A CORPORATION OF OHIO.

AIR FILTER.

Application filed October 12, 1925. Serial No. 61,960

This invention relates in general to improvements in air filters, and in particular to the production of an efficient and reliable means for separating dust from air by means 5 of a fabric that can be easily manufactured, and which lends itself readily to the operations necessary to form it into bags such as are in common use on domestic vacuum cleaners.

10 Investigation has shown that a mass of loose and slightly twisted textile fibres, such as cotton-batting, forms a very effective means for the separation of dust from air. Cotton-batting, however, is quite unwieldy, 15 and due to its lack of tensile strength is not a fit material from which to form bags which must retain and hold the dirt collected until it can be conveniently removed.

An object of this invention is to produce a 20 fabric which will approximate the air-filtering characteristics of cotton-batting, and at the same time possess sufficient strength in all directions to render it suitable for dust bags. Another object is the production of a 25 fabric of reasonable thickness and weight which will possess desirable air filtering characteristics.

Another object is the production of a multi-ply interwoven fabric in which the filling 30 yarns are very loosely twisted and held together by means of warp yarns which give the fabric the necessary tensile strength and finish.

With the foregoing and related objects in 35 view the invention consists in the novel combination and arrangement of the parts of the fabric, and in the novel character of the constituent parts thereof.

In the accompanying drawings illustrating 40 the invention:

Figure 1 illustrates the air filter shown in use with the common domestic type of vacuum cleaners;

Fig. 2 is a transverse section through the 45 fabric forming the filter;

Fig. 3 is a face view of the finished fabric.

Referring to the drawings, the air filter 50 consists of the fabric which for use with the ordinary type of suction cleaner is formed in the shape of a bag 10 which can be readily attached or detached from the suction cleaner 11.

The cloth from which the dust bag is 55 made, is referred to as a multi-ply interwoven fabric, inasmuch as it consists of a plurality of distinct layers of filling yarn

which are held together by means of warp yarns the character of which will be described later in detail.

In the air filter shown in the drawings 60 the fabric is composed of two layers A and B, which form the face and back of the fabric, respectively. It is to be understood, however, that two layers are shown for the purpose of illustration only and that our 65 invention is not limited to any particular number of layers.

The layer A is made up of filling stuffer 70 yarns 12 and face filling yarns 13 arranged alternately and secured together by the warp face yarns 14 which pass over two stuffers 12 and one filling 13 and then under one filling. The layer B is made up in the same manner and secured together by the warp back yarns 15. The two layers are 75 then firmly bound together by the warp binders 16 which pass over the face filling yarns 13 in one layer and then over the filling yarns 13 in the other layer.

The unique and novel filtering properties 80 of the fabric are due primarily to the characteristics of the filling yarns. In order to approximate as closely as possible in a woven fabric the structure of cotton-batting, these yarns are very loosely twisted; 85 for example, not more than 20 turns per inch and preferably between 4 and 16, merely sufficient to give them the necessary strength to stand up under the weaving process.

The functions of the warp threads which 90 are all hard twisted are to hold the loosely twisted filling yarns in place and to give the resulting fabric sufficient strength to withstand the strains to which it is naturally subjected in use. 95

We claim:

A multiple ply fabric for filters comprising loosely twisted yarns, each ply comprising alternately arranged relatively large and small loosely twisted yarns, each ply offset to 100 place a large yarn of one ply under a small yarn of an adjacent ply, and warp yarns securing the loosely twisted yarns in place.
